(57) **CLAIM**

The ornamental design for a combination pet coat and detachable liner, as shown and described.

DESCRIPTION

FIG. 1 is a top, front perspective view of a combination pet coat and detachable liner, showing the coat and liner combined and in a first configuration;

FIG. 2 is a bottom, rear perspective view thereof;

FIG. 3 is a top, front perspective view of the combination pet coat and detachable liner, showing the liner separately and in a second configuration;

FIG. 4 is a bottom, rear perspective view thereof;

FIG. 5 is a front elevation view thereof;

FIG. 6 is a rear elevation view thereof;

FIG. 7 is a left side elevation view thereof;

FIG. 8 is a right side elevation view thereof;

FIG. 9 is a top plan view thereof;

FIG. 10 is a bottom plan view thereof;

FIG. 11 is a top, front perspective view of the combination pet coat and detachable liner, showing the coat separately and in a third configuration;

FIG. 12 is a bottom, rear perspective view thereof;

FIG. 13 is a front elevation view thereof;

FIG. 14 is a rear elevation view thereof;

FIG. 15 is a left side elevation view thereof;

FIG. 16 is a right side elevation view thereof;

FIG. 17 is a top plan view thereof; and,

FIG. 18 is a bottom plan view thereof.

The broken lines in the drawings illustrate the portions of the combination pet coat and detachable liner, which form no part of the claimed design.
